(57) **CLAIM**

The ornamental design for a game call controller, as shown and described.

DESCRIPTION

In an exemplary embodiment the nature of this product is as a game call controller for operating a speaker or other remotely located module used to attract wildlife.

FIG. 1 is a right, top, front perspective view of a game call controller embodying my new design;

FIG. 2 is a front elevational view thereof;

FIG. 3 is a right side elevational view thereof;

FIG. 4 is a left side elevational view thereof;

FIG. 5 is a top plan view thereof;

FIG. 6 is a rear elevational view thereof; and,

FIG. 7 is a bottom view thereof.

The broken line representations of input/output connections and related structure in FIGS. 1–7; of fastener recesses and fasteners in FIGS. 3–6; of structural ribs in FIG. 6; and of button icons in FIGS. 1–2 and 4–7; show use and environment, and form no part of the claim.
